UNITED STATES PATENT OFFICE.

EDWARD F. SHELLABERGER, OF DE KALB, ILLINOIS.

MANUFACTURE OF BARB-WIRE.

No. 904,096.

Specification of Letters Patent.

Patented Nov. 17, 1908.

Application filed April 3, 1908. Serial No. 424,999.

To all whom it may concern:

Be it known that I, EDWARD F. SHELLABERGER, a citizen of the United States, residing at De Kalb, county of Dekalb, State of Illinois, having invented certain new and useful Improvements in the Manufacture of Barb-Wire, of which the following is a specification.

The object of my invention is the economical production of a single-strand barb-wire and to this end I take a round rod or wire (say of No. 9 gage) and flatten or deform it at intervals thus producing alternating portions of different diameters, the reduced portions having a slightly flattened or oval cross-section affording shoulders at their junction with the unreduced portions, these latter affording barb-seats and the shoulders preventing longitudinal movement of the barbs. The barbs are formed simultaneously with the flattening action and are loosely coiled on the barb-seats so as to be capable of rotating thereon. I accomplish these results preferably by instrumentalities which effect first the flattening of the wire, then forming and applying the barbs, and then spooling the barb wire in one continuous operation and without arresting the travel of the wire. To this end I can conveniently employ roller dies arranged in pairs for reducing the rod, the acting face of each roll being provided with grooves of such depth only throughout the major part of their length, and the rolls being so set, that the wire will be reduced to any desired extent, said grooves having a shorter, deeper portion producing between the pair an orifice as large or larger than the diameter of the wire so as to leave unreduced portions therein alternating with the reduced portions. A series of these die faces may be provided upon the periphery of each roll so that a single revolution of the die rolls will effect two or more reductions of the wire in sequence. For commercial purposes the barbs will be placed at predetermined intervals, say three to six inches apart, and it is practicable to use roller dies having a circumference of nine to eighteen inches and the number and length of the die faces may be varied as desired. I also prefer to employ barb-forming mechanism which will form and apply the barbs to the wire without interruption of its travel, and to accomplish this prefer to mount these wire coiling devices so as to have a travel

with the wire during the coiling operation and a return movement at the end of each coiling operation. The barb wire is reeled up on a spool in the usual manner and the several mechanisms will be so timed as to 60 perform their several operations in due order and relation.

In the accompanying drawings I have shown means well adapted for carrying out my invention but it will be understood that 65 said means, are intended to be typical only and may be substituted by others, and, considered in its broader scope, the method may be carried out by widely differing means or even by hand. The apparatus shown in the drawings comprises reels for supporting the rolls of two plain wires one of which forms the longitudinal strand and from the other of which the barbs are formed; a reel or spooler for reeling up the barb wire, a pair 70 of tension rolls for causing the wire to feed with a uniform speed; cylindrical die rolls for reducing the strand wire at intervals; means for feeding the wire from which the barbs are formed across the strand wire; 75 means for severing said wire to produce pieces of suitable length to form the barbs; and a coiler which wraps such short pieces of wire around the strand to form the barbs, 80 these several mechanisms being so timed as 85 to act in due order and relation whereby to produce such barb wire continuously and during its constant travel.

Some of the mechanisms shown in the accompanying drawings, particularly those 90 having to do with the supporting and movement of the wires and the forming and application of the barbs are shown in my Patent No. 704,710 of July 15, 1902, but the machine shown in said patent was intended 95 to produce a double strand barb wire and had no provisions for reducing the strand wire.

In the accompanying drawings Figure 1. is a plan view of a machine for carrying out 100 my invention, parts being omitted and others broken away; Fig. 2. is a side elevation of the same; Fig. 3. is a sectional elevation of the reducing rolls, showing their action upon the strand wire; Fig. 4. is a sectional 105 detail of the same; Fig. 5. is a diagrammatic view, particularly intended to show the relation of the wire supporting reels and the coiling spool to the operative mechanism of the machine; Fig. 6. shows a segment of 110

the barb wire in plan; and Fig. 7. a cross-section thereof through the reduced portion, the coil showing in side elevation.

It will only be necessary to describe in detail so much of the mechanism of this machine as is of novel construction, it being premised that a particular description of most of the operative parts of the machine can be found in my patent before mentioned and that the gearing and some of the other parts are of well-known construction and, therefore, need no particular description. Briefly described, there is mounted on the supporting frame-work 10 of the machine, 10 at the rear end thereof, a pair of regulating rolls 11, 12 between which the wire is fed through the wire-guide 13. These rolls may be smooth-faced or slightly grooved and their purpose is to produce an even feed of 15 the wire, said rolls being positively driven through a train of gearing from the main driving shaft 14. From this train of gearing the reducing rolls 15, 16 are also driven, said rolls being provided in their peripheries with grooves 17 of such depth that when the faces of the rolls are brought close together they will effect the reducing action upon a round rod or wire 18 there being provided deeper portions 17^a in the grooves 20 which will permit the passage of the wire therethrough without reduction, as is clearly indicated at 18^a. Preferably three or more of the grooves 17 will be formed circumferentially on the roll separated by deeper 25 grooves 17^a so that at each revolution of the roll three or more reductions will be effected. Preferably also three or more of these sets of peripheral grooves will be formed in each of the rolls so that when one becomes 30 worn the roll may be shifted laterally on or with its bearing so as to bring another set of die faces into action. This construction is indicated in Fig. 4.

The roll 16 may be mounted on a shaft 19. 45 in a suitable box or bearing and the roll 15 is mounted upon a shaft 20 and upon the bearings or boxes 21 thereof two threaded stems 22 are made to bear, said stems being provided at their upper ends with pinions 23 50 between which a pinion 24 carried by the stem 25 having a hand wheel 26 is placed so that by turning the hand wheel uniform pressure may be brought to bear upon the two ends of the shaft 21, thus providing for 55 the proper alinement of the roll 15. The rod 18 after passing through the reducing rolls is carried through a suitable wire guide 27 and coiler spindle 28. The spindle 28 is carried in a bearing 29 mounted upon a sliding table 30 its square shank 31 telescoping 60 with a driving arbor 32 mounted in a bearing 33 on a stationary part of the frame work. This arbor is driven by the vertically sliding rack 34 operating on the pinion 35 65 mounted on a short shaft having a gear

wheel 36 enmeshed with the driving gear 37 thereon. Upon the sliding table 30 is mounted the feed mechanism for the wire 38 from which the barbs are formed and the cut-off mechanism consisting of the adjustable block 39 and the knife 40, these mechanisms being so driven and timed as to feed a short length of the wire 38 across the wire 18 and sever it, whereupon the coiler will engage such short length of wire and 75 wrap it loosely about the barb-seat 18^a. From the barb forming mechanism the barbed wire is drawn out and wound upon a spool 40, Fig. 5.

The several mechanisms are so arranged 80 that when the strand wire is threaded through the machine and fastened to the spool (the latter being constantly revolved) such wire will be drawn between the regulating rolls and the reducing rolls and 85 through the hollow arbor and coiling spindle whereby such rod or strand will be flattened at regular intervals. The wire from which the barbs are formed will also be fed at regular intervals and the cut-off mechanism and 90 coiling mechanism will be operated to apply the barbs without interruption of the travel of the strand wire. To this end, the table carrying the feeding mechanism is given a reciprocating motion in the manner described 95 in my previous patent.

It will be understood that while the mechanism above described, with the exception of the reducing rolls, is of known construction that its combination and co-action with such reducing rolls is novel, so far as I am aware, and the reducing rolls I also believe to be of novel construction; by the means, mechanism or apparatus herein shown and described will be made the subject of a 105 separate application, the same not being herein claimed.

As my invention inheres in the method of producing single-strand barb-wire of the kind and character above described, the means which I have shown may be varied or even substituted by hand manipulation, but I prefer to use such novel mechanisms because thereby this product can be produced commercially. 110

The product, which is shown practically full-sized in Fig. 6, consists essentially of a single-strand wire reduced throughout the major portion of its length, such reduced portions alternating with unreduced portions, the reductions forming shoulders 18^b 115 at the ends of the unreduced portions serving to prevent too great movement of the barbs 18^c upon the strand. I have referred to these barbs as being loosely coiled upon their seats, and by this I mean that the coiling while producing a reasonably snug fit 120 does not act to compress the barb upon the wire and it is therefore free to turn axially and thus avoid frequent injury which 125

results to live stock from coming in contact with rigid barbs. It has long been desired to secure this result but heretofore where it has been attempted to mount barbs loosely upon a wire no practical provision has been made for forming stops or abutments in the strand wire to prevent the longitudinal movement of the barbs and hence the alternative of compressing the barbs upon the wire 10 has been suggested. This of itself is a difficult matter and besides does not afford any yielding character in the barb itself. On account of the difficulties above suggested and others which are obvious or will be 15 found upon an attempt to produce such single-strand wire according to old methods, no such wire has been heretofore offered as a marketable commodity.

By means of the apparatus above described I am enabled to produce single-strand barb-wire, having loose barbs, commercially, the machines I now have in use having a capacity of about two hundred and fifty (250) barbs per minute, such barbs being spaced three inches apart.

By observation of Figs. 4. and 7. of the drawings, it will be seen that the strand wire in the reduced portion is of oval cross-section, being slightly reduced in one diameter 20 and elongated in the other, thus providing the shoulders above mentioned, but it will be understood that the cross-section of the reduced portion will be varied by varying the formation of the die faces and that any 25 reducing action which will flatten or change and increase the lateral cross-section of the wire at intervals alternating with portions which are unchanged or remain of normal

cross-section is within the scope of my invention. It is also obvious that this flattening and compression of the strand wire will tend slightly to elongate the same. 40

The product is claimed in my allowed application Serial No. 401664 filed November 11, 1907. 45

I claim:

1. The herein-described method of making single-strand barbed wire which consists in flattening a round wire or rod at intervals whereby to increase its lateral cross-section 50 leaving portions thereof of normal cross-section and coiling short pieces of wire loosely about the unreduced portions to form barbs.

2. The herein-described method of making single-strand barb wire which consists in 55 feeding the wire continuously between moving surfaces, whereby to flatten and increase the lateral cross-section of the wire at intervals, and simultaneously coiling short wires loosely upon the unreduced portions to form 60 barbs.

3. The herein-described method of making single-strand barb-wire which consists in flattening a round wire or rod at intervals throughout the major portion of its length 65 whereby to increase its lateral cross-section and elongate the wire, the intervening shorter portions thereof remaining of normal cross-section, and then coiling short pieces of wire loosely about the unreduced 70 portions to form barbs.

EDWARD F. SHELLABERGER.
